[57] **CLAIM**

The ornamental design for a compressor for a vehicle air conditioner, as shown and described.

DESCRIPTION

FIG. 1 is a front elevational view of a compressor for a vehicle air conditioner;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front perspective view thereof;

FIG. 8 is a rear perspective view thereof; and,

FIG. 9 is a partial perspective view of the compressor of FIG. 1, mounted in a vehicle shown in phantom, the vehicle forming no part of the design of the present invention.
